UNITED STATES PATENT OFFICE.

THOMAS C. FISHER, OF ANDERSON, INDIANA.

GRAIN-CRADLE ATTACHMENT.

SPECIFICATION forming part of Letters Patent No. 372,791, dated November 8, 1887.

Application filed September 25, 1884. Renewed December 3, 1886. Serial No. 220,600. (No model.)

To all whom it may concern:

Be it known that I, THOMAS C. FISHER, a citizen of the United States, residing at Anderson, in the county of Madison and State of Indiana, have invented certain new and useful Improvements in Grain-Cradle Attachments, of which the following is a specification, reference being had to the accompanying drawings.

10 This invention relates to certain improvements in fastenings for grain-cradles, and has for its object to provide for adjusting the finger-post and cradle in relation to the snath and scythe, where they will be held by the usual post and finger-braces rigidly in position. These objects are attained by the means illustrated in the accompanying drawings, in which—

Figure 1 represents a perspective view of 20 the lower parts of the cradle-head and snath, showing the improved attaching device; Fig. 2, a central sectional view, and Fig. 3 a view of the slotted finger-post socket.

In the drawings, the letter A indicates the 25 snath fastening, composed of a base-plate, a, provided with the usual openings for the lug at the end of the scythe-shank, a ferrule, b, into which the end of the snath sets, and an aperture through which a bolt or screw is 30 passed to secure the fastening to the snath. The base-plate a is provided with a slot, c, and the ferrule, directly above said slot, with a hole, d.

B indicates a screw-bolt having an elongated 35 eye, through which passes the shank of the scythe. The threaded portion of the bolt passes through the hole in the ferrule, and is provided with a nut by which the loop or eye-bolt may be tightened upon the scythe-shank.

The fastening at its outer end is provided 40 with a notched extension, E, adapted to receive the peculiar shaped end of the finger-post socket, as will be presently described.

C indicates a socket-iron, one end of which receives the lower end of the finger-post D, 45 and the other end is provided with an eye having beveled edges e', adapted to facilitate the introduction of the notched extension E.

The cradle being put together, the attachment to the snath is made by inserting the extension E through the eye of the socket C and bringing the end portion into the notch of the extension, then drawing the finger-post inward toward the snath, and securing the whole firmly in the desired position by means of the ordinary devices, such as finger braces and post, or the like.

I am aware of Patent No. 226,630, granted April 20, 1880, and therefore do not seek to claim the construction therein claimed; but,

Having thus fully described my invention, what I claim as new, and desire to secure by Letters Patent, is—

In an attachment for grain-cradles, a snath-fastening provided with a notched extension 65 cast integral therewith, in combination with a finger post socket-iron provided with an eye having beveled edges to facilitate the introduction of the notched extension, as and for the purpose set forth.

In testimony whereof I affix my signature in presence of two witnesses.

THOMAS C. FISHER.
